US00D846972S

(12) **United States Design Patent** (10) **Patent No.:** **US D846,972 S**
(45) **Date of Patent:** **** Apr. 30, 2019**

(54) **CONNECTOR**

(71) Applicant: **Innovation First, Inc.**, Greenville, TX (US)

(72) Inventors: **Hoainam James Tonthat**, Greenville, TX (US); **William Beene**, Commerce, TX (US); **James Whitney Wilson**, Nevada, TX (US)

(73) Assignee: **Innovation First, Inc.**, Greenville, TX (US)

(**) Term: **15 Years**

(21) Appl. No.: **29/527,053**

(22) Filed: **May 15, 2015**

(51) LOC (11) Cl. **08-08**

(52) U.S. Cl.

USPC **D8/382**

(58) **Field of Classification Search**

(57) **CLAIM**

The ornamental design for a connector, as shown and described.

DESCRIPTION

FIG. 1 is a front perspective view of the first embodiment of the connector showing our new design in accordance with the present invention;

FIG. 2 is a front elevation view thereof;

FIG. 3 is a rear elevation view thereof;

FIG. 4 is a right side view thereof;

FIG. 5 is a left side view thereof;

FIG. 6 is a top plan view thereof;

FIG. 7 is a bottom plan view thereof; and

FIG. 8 is a rear perspective view thereof;

FIG. 9 is a front perspective view of the second embodiment of the connector showing our new design in accordance with the present invention;

FIG. 10 is a front elevation view thereof;

FIG. 11 is a rear elevation view thereof;

FIG. 12 is a right side view thereof;

FIG. 13 is a left side view thereof;

FIG. 14 is a top plan view thereof;

FIG. 15 is a bottom plan view thereof; and,

FIG. 16 is a rear perspective view thereof.

The broken lines shown in the various figures are included to show unclaimed subject matter only and form no part of the claimed design.

The dot-dash-dot broken lines in the drawings define the bounds of the claim and form no part thereof.

1 Claim, 6 Drawing Sheets
